(57) **CLAIM**

The ornamental design for a portable snow sports equipment locker, as shown and described.

DESCRIPTION

FIG. 1 is a front perspective view of our new design for a portable snow sports equipment locker.

FIG. 2 is a back perspective view of FIG. 1.

FIG. 3 is a front side elevation view of FIG. 1.

FIG. 4 is a back side elevation view of FIG. 1.

FIG. 5 is a side elevation view of the right and left sides, which are mirror images, of FIG. 1.

FIG. 6 is a top plan view of FIG. 1; and,

FIG. 7 is a bottom plan view of FIG. 1.

The features shown in broken lines in the drawing depict environmental subject matter only and form no part of the claimed design.

1 Claim, 4 Drawing Sheets
